UNITED STATES PATENT OFFICE.

HERBERT A. WILLIAMS, OF CHICAGO, ILLINOIS, ASSIGNOR TO RINDSBERGER MANUFACTURING CORPORATION, OF CHICAGO, ILLINOIS, A CORPORATION OF ILLINOIS.

DESIGN FOR A LAMP BASE.

Application filed January 14, 1926. Serial No. 16,054. Term of patent 3½ years.

To all whom it may concern:

Be it known that I, HERBERT A. WILLIAMS, a citizen of the United States, residing at Chicago, in the county of Cook and State of Illinois, have invented a new, original, and ornamental Design for Lamp Bases, of which the following is a specification, reference being had to the accompanying drawing, forming part thereof, in which—

Figure 1 is a top plan view of the base showing my new design, only a portion of the ornamentation being shown completed, it being understood that the remaining portion within the outline involves a mere repetition of that part more fully illustrated and Figure 2 is a front view thereof.

I claim:

The ornamental design for a lamp base as shown.

In witness whereof I affix my signature.

HERBERT A. WILLIAMS.
